[57] **CLAIM**

The ornamental design for a bakery basket, as shown and described.

DESCRIPTION

FIG. 1 is a top plan view of a bakery basket showing my new design, the bottom view being identical;
FIG. 2 is a side elevational view, the opposite side view being identical;
FIG. 3 is an end elevational view the opposite end view being identical;
FIG. 4 is a fragmentary sectional view taken on line IV—IV of FIG. 3;
FIG. 5 is a fragmentary sectional view taken on line V—V of FIG. 2;
FIG. 6 is a top plan view of a modified form of my design, the bottom view being identical;
FIG. 7 is a side elevational view, the opposite side view being identical;
FIG. 8 is an end elevational view, the opposite end view being identical;
FIG. 9 is a fragmentary sectional view taken on line IX—IX of FIG. 8; and
FIG. 10 is a fragmentary sectional view taken on line X—X of FIG. 7.

FIG. 1

FIG. 6

FIG. 7

FIG. 8

FIG. 9

FIG. 10
